COFFEE MAKER

Oscar S. Simpson, Jr., P.O. Box 85,
Houston, Tex. 77001

Filed Feb. 2, 1966, Ser. No. 889

Term of patent 14 years

(Cl. D44—26)

FIG.1 is a perspective view from below and to one side of a coffee maker embodying my design;

FIG. 2 is a perspective view from above and to one side of the coffee maker; and

FIG. 3 is a top plan view of the coffee maker.

I claim:

The ornamental design for a coffee maker, substantially as shown.
